UNITED STATES PATENT OFFICE.

STEPHEN J. KUBEL, OF WASHINGTON, DISTRICT OF COLUMBIA.

FEED-GAGE.

1,228,681.

Specification of Letters Patent. Patented June 5, 1917.

Application filed November 23, 1916. Serial No. 133,060.

To all whom it may concern:

Be it known that I, STEPHEN J. KUBEL, a citizen of the United States, residing in the city of Washington, District of Columbia, have invented certain new and useful improvements in Feed-Gages; and I do hereby declare the following to be a full, clear, and exact description of the invention, such as will enable others skilled in the art to which it appertains to make and use the same.

This invention relates to gages for machines involving mechanism for operating upon sheets or webs of paper, or other material, and has for its object to provide a novel form of sheet gage with electrical actuating means which may be operated to adjust the gage either from a point adjacent thereto, or from a remote point. It is common to employ gages of this character in printing presses and also in other machines where sheets or webs are fed, and the invention is applicable to gages of this character generally.

25 In the drawings:—

Figure 1 is a side elevation of the gage;

Fig. 2 is a plan view of the same;

Fig. 3 is a transverse section on line 11—11 of Fig. 5;

30 Fig. 4 is a similar section on line 12—12 of Fig. 5;

Fig. 5 is a longitudinal sectional view of the left-hand portion of the device, as shown in Fig. 2;

35 Fig. 6 is a bottom plan view of the armature and actuating pawls; and

Fig. 7 is a fragmental plan view of the guide-plate showing the relation of the fingers thereof to the gage-plate.

40 Referring to the drawings, the gage comprises a tubular housing 1, secured to the forward end of a box-like casing 1^a, which latter has a slidably adjustable connection on the top surface of a bracket 1^b. The ad-

45 justment of this bracket is effected by means of a thumb-screw 1^c engaging lugs on the members 1^a and 1^b, respectively. The bracket member 1^b is provided with a clamp collar 1^f, by means of which the gage is ad-

50 justably mounted on the rock shaft of the printing press when the gage is used in connection with a press, as will be understood. In order to securely lock the movable member of the gage to the bracket 1^b, there is 55 provided a vertical clamping screw 1^d which

passes through a slot 1^e in a lateral flange of the casing 1^a and engages the bracket 1^b.

Mounted for rotary movement within the tube 1 is a spindle 12 which carries at its forward end, a disk 16 which constitutes the gage plate and is associated with adjustable spring guard members 17. The rear end of the spindle 12 is in screw-threaded engagement with a boss or projection on the casing 1^a, as shown in Fig. 5, so that when said spindle 12 is rotated, it will be moved in and out longitudinally with respect to the tube 1 and will effect a corresponding movement of the gage plate 16, which latter, because of its circular contour, revolves between the fingers 12' of the feed plate 12'', over which the sheets or webs, which are indicated in Fig. 1 of the drawing at 16', are fed. The feed plate 12'', as disclosed in Fig. 7, is provided with spaced fingers 12', so that the gage plate 16 may extend below the surface of the feed plate and will not contact therewith. The advantage of this arrangement may be readily seen, inasmuch as it will insure the contacting of the web or sheet with a considerable portion of the face of the gage plate 16.

In order to effect the rotary movement of the spindle 12, in either direction, the latter is provided with two oppositely disposed ratchets 20 and 21, which ratchets are oppositely rotated by means of pawls 29^a and 29^b, respectively. These pawls are pivoted to the lower face of a swinging armature 27^a, said pawls being normally held in engagement with their co-operating ratchets by means of springs 31^a and 31^b, as clearly shown in Figs. 4 and 6, which springs are adapted to retain the pawl in their suspended positions, such as disclosed in Fig. 4, so

90 that upon the rotation of the spindle by one of the pawls, and the subsequent movement of the armature 27^a to its neutral position under the action of the springs 40, the other pawl will move on to the next succeeding tooth. The armature 27^a is pivoted on a pintle 27^b in the upper part of the casing 1^a and is disposed between two pairs of electro-magnets 25 and 26, which are secured

95 to the sides of the casing 1^a, so that when the respective pairs of magnets are energized, the armature will be swung in one direction or the other, and thereby rotate the spindle 12 a step at a time to either ad-

100 vance or retract the spindle. In order to 105

105 110 provide a vertical clamping screw 1^d which

maintain the armature normally in its central position, the said armature is provided with a T-shaped head portion, the opposite sides of which are engaged by flat springs 5 40—40, which springs, in turn, are secured to a cross piece 35' attached within the casing 1^a.

In order to lock the spindle 12 in any of its adjusted positions, there is provided an 10 electro-magnet 35 which consists of two spools attached to the under face of the cross piece 35', which electro-magnet 35 co-operates with an armature 36 which is pivoted on a cross rod 36' within the casing and is normally retracted from the magnet 35 by a 15 spring 36'', as shown in Fig. 3, to force a locking pawl or detent 37 into engagement with a ratchet 22 which is secured to the spindle 12. The circuits to the respective 20 magnets 25, 26 and 35 are similar to the circuits illustrated in Fig. 9 of the drawings in my Patent, No. 1,189,264, dated July 4, 1916, for paper feed gages, and said circuits are controlled or operated in the same manner, namely, by suitable push buttons arranged at some convenient point of control at a distance from the gage or by means of local push buttons or circuit closers p' and p^2 mounted on the casing 1^a.

30 With the apparatus, as described, installed, for example, on a printing press, when it is desired to adjust one of the gages, such adjustment may be effected either immediately at the gage by operating the proper push button p' or p^2 , or by operating one of the corresponding remote push buttons. If, for example, the operator observes that one of the gages should be advanced slightly, he pushes the appropriate 35 remote button, for instance, and thereby energizes the magnets 25 or 26 and also the magnet 35, which latter unlocks the spindle 12 and the former of which rotate the same one step. If this extent of adjustment is not 40 sufficient, the actuation of the push button is repeated until the desired adjustment is obtained, which adjustment, it will be understood, proceeds step by step. Instead of effecting the adjustment from the point of 45 distant control, the operator may adjust the gage by means of either of the push buttons p' or p^2 located on the casing 1^a.

It is obvious that the invention may be applied to any of the well-known types of 50 gages, or may be substituted for the various gages now employed in machines involving the feeding of sheets or webs of materials, and for effecting adjustment of gages or parts of machines from a point of distant 55 control.

What I claim is:—

1. A feed gage comprising a gage plate,

a rotary spindle for adjusting the plate, oppositely disposed ratchets on said spindle, and means for actuating the spindle which 65 includes oppositely disposed electro-magnets, an armature disposed between the same, and oppositely disposed pawls carried by the armature and co-operating with the respective ratchets. 70

2. A feed gage comprising a gage plate, a rotary spindle for adjusting the same, oppositely disposed ratchets secured to the spindle, means for adjusting the spindle including oppositely disposed electro-magnets, an armature arranged between the same and carrying pawls which co-operate with the respective ratchets, and means for normally preventing the rotation of the spindle. 75

3. A feed gage comprising a gage plate, 80 a rotary spindle for adjusting the same, a pair of oppositely disposed ratchets on said spindle, oppositely disposed spaced electro-magnets, a pivoted armature arranged between the magnets and carrying pawls arranged to co-operate with the ratchets, and resilient means for maintaining the armature in a neutral position between the magnets. 85

4. A feed gage comprising a gage plate, 90 a rotary spindle for adjusting the same, oppositely disposed electro-magnets, a pivoted armature arranged between the magnets and adapted to be attracted by either, and means on the armature for engaging the spindle to 95 rotate the same in either direction.

5. A feed gage comprising a gage plate, 100 a rotary spindle for adjusting the same, oppositely disposed electro-magnets, a pivoted armature arranged between the magnets and adapted to be attracted by either, means on the armature for engaging the spindle to 105 rotate the same in either direction, means for normally locking the spindle, and means for disengaging the locking means simultaneously with the actuation of the armature in either direction.

6. The combination with a feed plate, of 110 a feed gage including a gage-plate rotatable on an axis passing through the same, said gage-plate extending below the surface of the feed plate.

7. A feed gage comprising a rotatable and longitudinally movable spindle, a gage plate secured to one end thereof, and means for 115 causing the rotative and longitudinal movements of the former.

8. A feed gage comprising a rotary spindle, a circular gage plate secured thereto, and means for adjusting the spindle and 120 plate longitudinally of the former.

In testimony whereof I affix my signature.

STEPHEN J. KUBEL.
